UNITED STATES PATENT OFFICE.

GEORGE L. BARRETT, OF SPRINGFIELD, OHIO.

SIGNALING DEVICE.

1,103,860.

Specification of Letters Patent. Patented July 14, 1914.

Application filed September 6, 1913. Serial No. 788,426.

To all whom it may concern:

Be it known that I, GEORGE L. BARRETT, a citizen of the United States, residing at Springfield, in the county of Clark and State 5 of Ohio, have invented certain new and useful Improvements in Signaling Devices, of which the following is a specification, reference being had therein to the accompanying drawing.

10 This invention relates to signaling devices and more particularly to signaling devices actuated by some part of a car to announce its approach at a remote point. In devices of this kind the signaling devices are placed 15 at convenient points, as in residences more or less remote from the street railway or other track, and devices are placed along the track at a distance more or less remote from the station or crossing, which devices will be 20 actuated by the car to operate the signals and thus announce the approach of the car.

The object of the present invention is to provide a very simple device of this kind which will be actuated by the trolley wheel 25 to positively close a signal circuit; which will lock the circuit breaker and closer in its closed position; and which will be actuated by the trolley wheel to unlock the circuit breaker and closer and permit the same 30 to open.

A further object of the invention is to provide a device of this kind which will be very simple in its construction, very strong and durable and very positive in its operation.

35 In the accompanying drawings, Figure 1 is an elevation showing my invention applied to a trolley wire; Fig. 2 is a perspective view of the circuit breaker and closer 40 and the connections between the same and the actuating member; Fig. 3 is a detail view of the actuating member and the locking device therefor; Fig. 4 is a detail view 45 of the trip devices for the actuating member; Fig. 5 is a detail view of one of the brackets and the connection between the actuating member and the circuit breaker and closer; and Fig. 6 is a perspective view 50 of a slightly modified form of the invention.

55 In these drawings I have illustrated one embodiment of my invention and have shown the same as applied to a trolley wire 1 supported from the trolley post 2 in an ordinary manner. I have not illustrated the car but have shown at 3 a trolley wheel, such as is ordinarily carried by electric cars. I have

shown the signaling device and circuit diagrammatically, it being understood that this device may be of any suitable kind, such, for example, as the ordinary electric bell, 60 which is indicated at 4 in the circuit 5. The current for actuating the signal may be derived from any suitable source and is diagrammatically illustrated as comprising a battery 6. Connected in the circuit 5 is a 65 circuit breaker and closer adapted to be actuated in the manner hereinafter described for closing the circuit to actuate the signal and announce the approach of the car. This circuit breaker and closer, or switch, may 70 be mounted at any convenient point but I prefer to mount the same upon one of the trolley poles 2 and to that end I have shown the same as carried by a bracket 7 which, in the present instance, is in the form of a right 75 angle adapted to have the two arms thereof placed on different sides of the trolley pole. By making the bracket in this form and providing each arm thereof with a plurality of bolt holes it is possible to apply the 80 bracket to posts of different shapes and different kinds, it being apparent that while the bracket will fit snugly about a post that is square or rectangular in cross section, it can also be connected to a round post and 85 that the plurality of bolt holes spaced along the arms will enable it to be connected with round posts of different diameters and to have the bolt or other connecting device arranged centrally of the post. 90

Mounted on the bracket 7 are contact members 8 and 9 which are connected to the bracket, preferably through the medium of insulating material 10, and which are connected with the respective sides of the signal 95 circuit 5 by means of the usual binding posts. The contact member 9 is movable and is preferably in the form of a lever or arm pivotally mounted at one end and spring actuated to hold the same normally 100 out of engagement with the contact member 8. As here shown a coiled spring 11 is connected with the lever 9 and with a part of the bracket 7. This movable contact member 9 is also connected with an actuating 105 member to which movement is imparted by the trolley wheel of the car. As here shown the actuating member comprises a rod 12 supported above and extending substantially parallel with the trolley wire 1 having one 110 end supported by links 13 from a bracket 14, which bracket is preferably mounted on the

trolley wire. The opposite end of the actuating member 12 is supported on another bracket, 15, also mounted on the trolley wire, by means of links 16 which extend downward beyond the bracket 15, as shown at 17, into the path of the trolley wheel and constitute trip arms by means of which longitudinal movement may be imparted to the actuating member. These trip arms preferably have their lower ends grooved, as shown at 18, to receive the edges of the trolley wheel and prevent the same slipping off the edge of the trip arms without actuating the same. With the trip arms constructed as shown the trolley wheel must pass beneath the arms and in doing so will rock the same about either pivotal support on the bracket 15 and thus impart longitudinal movement to the actuating shaft 12. The actuating member may be connected with the movable member of the circuit breaker and closer in any suitable manner but in the arrangement here shown the circuit breaker and closer is arranged at one side of the trolley wire and the connection is a flexible one which extends about an axis arranged beyond the end of the actuating member and here shown as a stud 19. While any suitable flexible connection may be passed about this axis in any desired manner, that chosen for the purpose of illustration consists of two flexible members 20 and 21, the former connected with and insulated from the movable contact arm 9 and the other, 21, connected with the adjacent end of the actuating member 12. The two flexible members are connected one to the other by a suitable device mounted on the stud 19. In the present instance this device is a disk 22 having ears to which the respective flexible members are connected. It will be apparent that a pull upon the actuating member 12 will rock the disk 22 and thus draw the contact member 9 toward its co-operating contact member 8 and close the circuit 5 through the signaling device, this operation taking place whenever a trolley wheel moving in the direction of the arrow in Fig. 1 engages the trip arm 17. In order that the signal may be operated for a sufficient length of time to give ample notice of the approach of a car I provide a locking device to retain the circuit breaker and closer in its closed position until it has been positively released. To accomplish this I have pivotally mounted upon the bracket 14 a latch 23 extending above and parallel with the actuating member 12 and having its free end bifurcated, as shown at 24, thus forming guide arms which extend on opposite sides of the actuating member and also providing a shoulder adapted to engage a lug 25 on the upper edge of the actuating member 12. The lug 25 is so arranged with relation to the latch 23 that

when longitudinal movement is imparted to the former to close the circuit the latch will drop in the rear of the lug 25 and thus prevent the return of the actuating member to its normal position. The arms of the bifurcated portion of the latch extend downward to points adjacent to the trolley wire where they will be engaged by the flanges of the trolley wheel when the latter passes these points, thereby raising the latch, releasing the actuating member and permitting the movable contact member 9 to be moved into its open or normal position by the spring 11.

While I have shown and described one embodiment of my invention it will be understood that this has been chosen for the purpose of illustration only and that I do not desire to be limited to the details of construction shown and described, for obvious modifications will occur to a person skilled in the art. For example, where it is desired to use the device with a source of electrical energy which is irregular I may, if I desire, mount a storage battery 26 in a suitable location, as upon the side of the post, and place the circuit breaker and closer either upon or adjacent to the storage battery. The battery will then be charged while the circuit is alive and will operate the bell when the source of electrical energy has died out temporarily. Otherwise, the construction and operation will be substantially that above shown and described. Also it may, under certain circumstances, be desirable to provide a stop 27 on one of the brackets to limit the movement of the actuating member and thus prevent the trip arms being carried into a position where they will either be improperly acted upon by the trolley wheel or will not be engaged by the trolley wheel at all. As here shown the stop is formed integral with the bracket 14 but it will be obvious that the bracket may be mounted in any suitable manner and at any suitable point. Further, if desired, the flexible members 20 and 21 may be adjustably connected with their respective parts and in the present instance, I have shown the member 20 as provided with a turn buckle device having a hook at one end, as shown at 28, by means of which it may be connected with the contact lever 9 and its length adjusted after the connection is made.

Having thus fully described my invention, what I claim as new and desire to secure by Letters Patent, is:—

1. The combination, with a trolley wire, a signal circuit, a circuit breaker and closer supported independently of and at a point remote from said trolley wire, an actuating member supported adjacent to said trolley wire and operatively connected with said circuit breaker and closer, and devices arranged to be successively engaged and actu-

ated by a trolley wheel to positively control the movements of said actuating member, which movements control the opening and closing of the circuit breaker and closer.

5 2. The combination, with a trolley wire, a signal circuit, and a circuit breaker and closer supported independently of and at a point remote from said trolley wire, of brackets mounted on said trolley wire and spaced apart, an actuating member carried by said brackets and capable of longitudinal movement relative to said trolley wire, an operative connection between said actuating member and said circuit breaker and closer, 10 15 a device connected with said actuating member and arranged to be engaged by a trolley wheel to impart movement to said actuating member and close said circuit, a detent to hold said actuating member in a position 20 to retain said circuit closed, and means actuated by the further movement of said trolley wheel to release said actuating member from said detent.

3. The combination, with a signal circuit comprising a signal and a circuit breaker and closer, of a trolley wire, brackets carried by said trolley wire and spaced apart, a rod mounted on said brackets for longitudinal movement, an operative connection between said rod and said circuit breaker and closer, trip arms connected with said rod and arranged to be actuated by a trolley wheel moving along said trolley wire, a latch carried by one of said brackets and adapted 30 35 to engage a part carried by said rod, said latch being arranged to be engaged by the trolley wheel to move the same out of engagement with said part of said rod.

4. The combination, with a signal circuit comprising a signal and a circuit breaker and closer, of a trolley wire, brackets mounted thereon and spaced apart, a rod, a link connecting one end of said rod to one of said brackets, another link connecting the 45 other end of said rod to the other of said brackets and extending beyond said bracket to form a trip arm, and means controlled by a trolley wheel for retaining said rod in a position to retain said circuit breaker and 50 closer in a closed position.

5. In a device of the character described, the combination, with a trolley wire, a signal circuit, and a circuit breaker and closer for the signal circuit comprising a movable 55 member to open and close said circuit, of an actuating rod mounted adjacent to said trolley wire, operatively connected with said

movable member and capable of longitudinal movement relatively to said wire, a trip arm connected with said actuating rod and extending into a position to be engaged by a trolley wheel moving along said trolley wire and thereby cause said movable member to be actuated, and a latch arranged to engage said actuating rod and hold the same 60 65 in a position to retain said movable member in its open position and to be released from said rod by the further movement of said trolley wheel.

6. In a device of the character described, 70 the combination, with a trolley post, a trolley wire supported thereby, a signal circuit, and a circuit breaker and closer for said signal circuit mounted on said trolley post, said circuit breaker and closer comprising 75 an angular bracket having a plurality of holes in each arm thereof, and contact members mounted on and insulated from said bracket, of an actuating rod mounted adjacent to said trolley wire, operatively connected with said circuit breaker and closer and capable of longitudinal movement, trip arms connected with said actuating rod and extending into the path of a trolley wheel moving along said trolley wire, a latch 80 85 adapted to engage said actuating rod and to be released from said rod by the further movement of said trolley wheel.

7. In a device of the character described, 90 a signal circuit, a circuit breaker and closer connected in said signal circuit and comprising a movable member, a spring connected with said movable member to hold the same in its inoperative position, a trolley wire, an actuating rod supported adjacent to said trolley wire and capable of longitudinal movement, an operative connection between said rod and the movable member of said circuit breaker and closer, trip arms connected with said rod and arranged 100 to be engaged by a trolley wheel moving along said wire, and a latch arranged to engage said rod and hold the same against the tension of said spring, said latch having parts adapted to be engaged by said trolley 105 wheel to move the latch out of engagement with said rod.

In testimony whereof, I affix my signature in presence of two witnesses.

GEORGE L. BARRETT.
